UNITED STATES PATENT OFFICE.

GEORGE X. WENDLING, OF SAN FRANCISCO, CALIFORNIA.

SEPARABLE-COMPARTMENT CONTAINER.

Application filed February 17, 1923. Serial No. 619,602.

To all whom it may concern:

Be it known that I, GEORGE X. WENDLING, a citizen of the United States, residing at city and county of San Francisco, and State 5 of California, have invented certain new and useful Improvements in Separable-Compartment Containers, of which the following is a specification.

This invention relates to a type of receptacle provided with compartments and which for shipping purposes is capable of transporting as a single unit, but when the contents thereof is sold, is capable of dividing into a plurality of closed containers. The 10 container is particularly adapted for use in the marketing of cherries, grapes, tomatoes, or in fact, any commodity the shipper desires to market cheaply and without damage to the same occasioned by the opening of the container when it is desired to seal a portion of the quantity of the entire unit. The object of my invention is accomplished without opening the original package or in any manner disturbing the 15 contents thereof but by simply cutting the walls enabling the separation of the compartments into separate independent packages.

With the above mentioned and other objects in view, the invention consists in the novel construction and combination of parts hereinafter described, illustrated in the accompanying drawings, and set forth in the claims hereto appended, it being understood 20 that various changes in the form, proportion, size and minor details of construction within the scope of the claims may be resorted to without departing from the spirit or sacrificing any of the advantages of the invention.

To more fully comprehend the invention, reference is directed to the drawings wherein:

Figure 1 is a perspective view of the container having duplicate braces to which the 25 overlapping wall forming flaps are secured, affording an end wall for the separated units when the same are detached.

Fig. 2 is a sectional view taken on the line 2—2 of Fig. 1.

Fig. 3 is a view similar to Fig. 1 but illustrating the flap edges overlapping in superimposed relation.

Fig. 4 is a sectional view on line 4—4 of Fig. 3.

In the embodiment of my invention illustrated, the numeral 1 indicates preferably

a strip of veneer, the ends of which are united together so that said strip forms a rectangular open frame structure as illustrated. The end walls 2 and 3 of this frame 60 structure are united in their center by the longitudinally separable brace 4. This brace is preferably constructed of two pieces of material contacting on their meeting surface 5 and each piece extending the full 65 width between the top and bottom edges of the walls 2 and 3. The pieces are secured at their ends to the respective walls by nails, tacks, or other securing means 6.

Secured in any manner to the inner faces 70 of opposing side walls 7 of the frame are the sheets 8 of a width co-extensive with the length of the side wall, and of a length slightly greater than twice the width of the frame, plus the depth of the side wall. These 75 respective sheets are secured in position by any suitable means as for example, an adhesive, and at points adjacent the longitudinal edges of the side walls 7. The sheets are bent as at 9 forming closure flaps 10 80 and 11, these flaps each being of a length slightly greater than one-half the width of the completed carton or receptacle, so that when folded down in contact with the upper edge of the dividing brace 4, their free ends 85 will overlap as at 11' in Figs. 3 and 4 of the drawing. After being folded down and overlapped to retain the contents of the receptacle therein the edges of the flaps are secured to the respective braces 4 by nails 90 or other securing means 12 driven therethrough, the means 12 being arranged in parallel rows as in the drawing.

In Fig. 1, the free edges of the members 10 and 11 do not overlap in superimposed relation but the same are scalloped or cut to overlap the upper surface of the brace 4 in interlocking relation providing a smooth surface without a center ridge for the receptacle. In this construction the nails for 100 securing each flap to each separable portion of the brace, are employed. To afford a handle for carrying the container or the individual separated parts, I have provided in the flaps 10 and 11 parallel finger receiving 105 slots 14 separated by a grip portion 15.

When it is desired to divide a container of this present type, it is only necessary to cut through the closure flaps and end walls 2 and 3 at a point in alignment with the meeting surfaces 5 of the members 4. This permits of the separating of the container into 110

two parts without in any manner disturbing the contents of either compartment. It will be observed that each portion of the longitudinally separable brace affords a wall for each compartment when the original package is divided. It will be also observed that the brace affords a strengthening means centrally of the package, enabling the same if desired to be constructed of extremely light weight material thus affording a material saving in the construction of the package and reducing its weight and thereby affording a saving in transportation cost.

I claim:

1. A shipping container comprising connected side and end walls forming a rectangular wall structure, complementary top and bottom closure forming members hinged at corresponding edges of said side walls to enable complementary members to fold toward each other, and the front edges to overlap, a longitudinally separable brace within said rectangular structure dividing the same into separate compartments, one face of each of which is closed by one of said complementary members, and means for securing the overlapping edges of said corresponding top and bottom closure members to each separate portion of the brace and the structure end walls to the ends of the respective separable portion of the brace whereby on the cutting of the overlapping portions of the closure forming members and the end walls, said container is capable of dividing into two closed compartments.
2. A container including connected side and end walls adapted for positioning to

form a substantially rectangular frame, top and bottom wall forming flaps hinged at one edge with their free edges free to fold toward each other in overlapping relation, a pair of adjacent parallel parts extending across the interior of the frame and secured at their opposite ends to opposing wall members, said overlapping edges of said flaps each adapted for securing to corresponding edges of each part, whereby on the severing of said flaps and end walls at a point between their points of attachment to the respective parts, said container is capable of dividing into two closed parts.

3. A container including connected side and end walls adapted for positioning to form a substantially rectangular frame, top and bottom wall forming flaps hinged at one edge with their free edges free to fold toward each other in overlapping relation, one of said flaps provided with parallel separated cut portions affording between them a hand gripping portion providing a handle, a pair of adjacent parallel parts extending across the interior of the frame and secured at their opposite ends to opposing wall members, said overlapping edges of said flaps each adapted for securing to corresponding edges of each part, whereby on the severing of said flaps and end walls at a point between their points of attachment to the respective parts said container is capable of dividing into two closed parts.

In testimony whereof I have signed my name to this specification.

GEORGE X. WENDLING.
